UNITED STATES PATENT OFFICE.

GOTTFRIED PIETZKA, OF WITKOWITZ, MORAVIA, AUSTRIA-HUNGARY.

ROTARY DOUBLE-FLAME FURNACE.

SPECIFICATION forming part of Letters Patent No. 398,973, dated March 5, 1889.

Application filed March 16, 1888. Serial No. 267,411. (No model.) Patented in Austria-Hungary November 1, 1886, No. 30,909 and No. 55,631, and in Germany January 11, 1887, No. 40,218.

To all whom it may concern:

Be it known that I, GOTTFRIED PIETZKA, a subject of the Emperor of Austria, residing at Witkowitz, Moravia, Empire of Austria, have 5 invented new and useful Improvements in Rotary Double-Flame Furnaces, (for which I have received Letters Patent in Germany, No. 40,218, January 11, 1887, and in Austria, No. 30,909, tome 36, fol. 2,554, and Hungary, No. 10 55,631, tome XX, fol. 2,347, dated November 1, 1886,) of which the following is a specification.

The invention relates to furnaces used for puddling and welding pig-iron or for manufacturing Martin steel.

15 The object of the invention is to provide a new and improved furnace adapted to be turned so as to avoid loss of heat and time in clearing away the iron and also to increase 20 the quantity and quality of the product.

The invention consists of certain parts and details and combinations of the same, as will be fully described hereinafter, and then 25 pointed out in the claims.

Reference is to be had to the accompanying 30 drawings, forming a part of this specification, in which similar letters of reference indicate corresponding parts in all the figures.

Figure 1 is a longitudinal sectional elevation 35 of the improvement. Fig. 2 is a sectional plan view of the same on the line $x-x$ of Fig. 1. Fig. 3 is a vertical cross-section of the same on the line $y-y$ of Fig. 1. Fig. 4 is an enlarged 40 sectional side elevation of a modified form of turn-table. Fig. 5 is a like view of another modification of the same. Fig. 6 is a sectional side elevation of a modified form of a device for raising the turn-table. Fig. 7 is a like view 45 of a modified form of the same. Fig. 8 is a sectional plan view of the same on the line $z-z$ of Fig. 7. Fig. 9 is a sectional side elevation 50 of another modification of the turn-table. Fig. 10 is a like view of still another modification of the turn-table, and Fig. 11 is a sectional plan view of a modified form of the bed 55 of the furnace.

The improved furnace is provided with the usual auxiliary apparatus, of any approved construction, such as blasting-engines, water-cooling pipes for the bridge-walls, &c.

The furnace consists principally of a stationary part and a turning part. The stationary part is provided with a fire box or chamber, F, which, according to the fuel used, may be provided either with horizontal grates 55 or with stepped grates, or it may also be arranged for gas-heating, in which case the grate is dispensed with.

The apparatus for producing the blast may be of any approved construction, and is 60 shown at V in Fig. 2. The suction-pipe W' of the blasting apparatus is so arranged as to suck up the highly-heated air from below the bottom plate of the turning part of the furnace and discharge the same through the outlet-pipe W into the fire box or chamber F. The latter is provided on top with an outlet-channel, C, adapted to register alternately with the channels C' and D, leading to or from, as the case may be, the turning part of 70 the furnace. The channels C' and D are also adapted to register alternately with the channel D', leading to the fixed chamber E and located directly opposite the channel C of the fire box or chamber F.

75 The turning part of the furnace is formed principally of a double hearth, the parts K K' of which are separated from each other by the water-bridge R', but are in communication with each other and open into the channels C' and D, above described. Each of the parts K K' of the hearth is provided with working-openings T, arranged opposite each other, as plainly shown in Fig. 2. Each portion K K' of the hearth is also provided on 80 its outer end with a fire-bridge, R and R², respectively, and with suitable water-cooling contrivances.

85 The movable part of the furnace terminates at the surfaces A A' and B B' (shown as lines 90 in the longitudinal section of Fig. 1) of a truncated cone, the point of which is turned downward and in line with the axis of the turning part of the furnace. The whole furnace is constructed in such a manner that the masonry, which is principally made of fire-proof bricks, is placed in cast-iron boxes and firmly held together by armor-plates, &c.

95 As before stated, the suction-pipe of the blasting apparatus is connected with the bot- 100

tom of the turning part of the furnace, and in order to heat the air as much as possible I cause the air to flow through a channel, L, which is as long as possible, and is formed below the bottom plate of the furnace under the double hearth K and K' by means of longitudinal partitions S, of sheet-iron. Two long pipes, G and G', are arranged at the extreme ends of this channel L, and one of the said pipes is adapted to take up the air from the outside, so that the air enters in a cold state below the bottom plates of the double hearth K and K', whereby the latter is cooled, as a part of the air is taken up by the said bottom plate. The other short pipe is immersed in a receptacle filled with water, in order to render it perfectly tight, and the air passes out through this short pipe into the suction-pipe W', connected with the blasting apparatus V. The air discharged from the blasting apparatus is in a compressed state and flows partly as upper blast along the fire-walls of the fire box or chamber F and partly through the grate, as under grate-blast. By introducing fresh air continuously under the bottom plate of the double hearth K and K' the furnace is cooled off.

The bottom plate of the hearth K K' rests firmly on supports M, secured to the plate P, held on the upper end of a plunger, H, which moves up and down in the cylinder Z, the walls of which must be sufficiently strong to resist the pressure corresponding to the weight of the movable part of the furnace. The lifting of the plunger H is effected by means of a hand-pump or an accumulator, which may be fed by means of a pump operated by hand or other power. When the movable part of the furnace has been raised to a considerable height and the two working parts K and K' of the hearth have been charged as uniformly as possible, the furnace is turned by hand or chain-gear, or by any other suitable means. As the plunger H forms the trunnion, so that the friction is relatively small, it is possible to turn the movable part of the furnace by hand. When the movable part of the furnace is in its raised position, as shown in Fig. 1, the plunger is discharged and the weight of the furnace is transferred to suitably-arranged rails located below the bottom of the movable part of the furnace. The purpose of this turning arrangement of the furnace is as follows:

When the furnace is heated and the two working parts of the hearth are ready for action, material is introduced first into the part K next to the fire box or chamber F. When the material is molten, the other part, K', is charged. In the first working part of the hearth the charge is treated in the usual way and finally worked out. During this time the iron is heating in the second part, K', and becomes perfectly liquid. When the first part, K, is entirely worked out, the turning part of the furnace is lifted by means of a hydraulic contrivance to a suitable pipe and

turned one-half of the revolution, the hydraulic contrivance operating on the plunger H so as to raise the same in its casing Z. The delivery-cock X (see Fig. 1) of the casing Z is then opened, so that the water will flow out of the casing Z and the turning part of the furnace will settle upon its support, whereby the fire bridge and flue will be again perfectly joined with each other. As the joining surfaces A A' B B' are conically tapered downward, there will be sufficient play; but after turning the lifted furnace and when the latter has been lowered a perfectly-tight joint will be formed. The positions of the parts K K' of the hearth have then been reversed, and the channel D of the part K now connects with the channel C of the heating-chamber F, and the channel C' of the part K connects with the channel D', leading to the chimney E. The material is now treated as usual in the second working part, K', which is next to the fire box or chamber F, and a fresh charge is immediately introduced in the first working part, which is now turned toward the channel D'. The above-described operation is continually repeated as long as desired.

The double furnace, instead of being lifted at its plunger H by hydraulic means, may be lifted either by steam-pressure or by a lifting-jack. Fig. 4 shows an arrangement in which the trunnion H, working as a plunger-piston in the casing or cylinder Z, is lifted by the direct action of steam. The steam enters through the two-way cock a at b below the plunger H and lifts the latter. The lifting action continues until the aperture c is uncovered by the lower end of the said plunger H, so that the steam may work through the pipe d, connected with the said opening c. The plunger-piston can thus be kept under steam-pressure at the desired height and the furnace may be turned. The waste water may be let off through the two-way cock a.

Fig. 5 illustrates the same construction, with the addition of a device for regulating the position of the plunger H. The latter is raised to the desired height, while at the same time the screw e is set in such a way that it takes up the whole weight of the piston. The screw e moves in a nut, f, formed into a toothed wheel, into which meshes a spur-wheel, g, operated by a hand-wheel, h. When the latter is turned, the wheel g imparts a rotary motion to the nut f, which turns the screw e and raises and lowers the same and the plunger H accordingly.

In Fig. 6 conical wheels f' and g' are used for moving the nut f and the screw e, instead of using spur-wheels, as shown in Fig. 5.

In Figs. 7 and 8 a construction is shown for raising the plunger H by hand. The frame k, carrying the pivot l, supports the lower end of the plunger H. The pivot l and its frame k are raised and lowered by means of screws m and m', connected with the said frame k and turning in suitable nuts held in the base of the casing Z. The screw m carries a hand-

wheel, *h*, and both screws *m* and *m'* are provided with crank-arms connected with each other by a frame, *n*, so that when the hand-wheel *h* is turned the frame *n* and the crank-arms impart a simultaneous rotary motion to the screws *m* and *m'*, whereby the frame *k* and its pivot *l* are raised and lowered.

Fig. 9 shows another device for lifting the plunger II. The nut *o* is provided with a hand-wheel, *h*, and carries the rollers *p*, turning on a suitable circular track. The screw *q* screws in the lower end of the nut *o*, and is guided in its up-and-down movement by a prism, *r*. Instead of a hand-wheel, *h*, a drawing-rod 15 may be applied to the nut *o*, and the motion to be produced can be accomplished by a horse attached to the said rod.

In the construction represented in Fig. 10 the plunger II is raised by means of an eccentric, *S*, secured on a shaft moved by hand or other power. According to the local conditions one or the other of the above-described contrivances may be applied. In cold countries—such as the northern part of Russia, 25 for instance—where the disposition of the water to freeze renders its use impracticable during the winter season, the hydraulic lifting contrivance may preferably be replaced by the construction shown in Figs. 4 and 6. 30 When neither water nor steam is obtainable, one of the constructions represented in Figs. 7 to 10 may be employed. Furthermore, it is not necessary for the parts K K' of the hearth to be of the identical same shape and size 35 shown in Fig. 11. The principal point in constructing the furnace consists in distributing the weight equally around the trunnion or plunger II and in making the channels C' and D register with the channels C and D'. 40 Having thus fully described my invention, I claim as new and desire to secure by Letters Patent—

1. The combination, with a fire-box and a stack or chimney, of a double hearth or heating-chamber constructed and arranged to connect alternately with the exit-flue of the fire-box and with the chimney, and means for rotating said hearth, substantially as described. 45

2. The combination, with a fire-box and a stack, of a double hearth arranged between the fire-box and stack, a turn-table supporting the said hearth, and means for operating said turn-table, substantially as herein shown and described. 50

3. The combination, with a fire-box and a stack, of a double hearth arranged between the fire-box and stack and provided with opposite channels leading therefrom, a turn-table supporting the hearth, and means for raising, lowering, and turning the said turn-table, substantially as herein shown and described. 55

4. In a furnace, the combination, with a fire-box and a chimney opposite the fire-box, of a double hearth between the fire-box and chimney and provided with an air-channel below the bottom thereof, and a blast-engine connected with the said air-chamber and with the fire-box, substantially as herein shown and described. 65

5. In a furnace, the combination, with a hearth, of a partitioned channel, I, below the bottom of the hearth, and connected at one end with the open air and at the other end with the suction-pipe of a blast-engine, substantially as described. 70 75

In testimony whereof I have signed my name to this specification in the presence of two subscribing witnesses.

GOTTFRIED PIETZKA.
